Application June 25, 1935, Serial No. 28,348
In Great Britain July 20, 1934

24 Claims. (Cl. 131—39)

This invention is for an improved method of and apparatus for feeding tobacco to cigarette making or tobacco packaging machines.

It has hitherto been customary in feeding cut 5 tobacco to comb out tobacco from an irregular mass and shower it over a moving surface to form what is known as a "carpet", this being based on the principle that as the thickness of the "carpet" is built up by the shower, the known 10 irregularities ever present in the shower are spread, intermixed, averaged or equalized.

This previous method of feeding tobacco is open to the objection that the equalization is largely a matter of chance, as there is no controlling or compensating factor. For instance, 15 any heavy portions of the "carpet" may be receiving successive heavy portions of the shower, there being no positive factor (apart from probability) to ensure that heavy portions of the "carpet" shall receive compensating lighter portions 20 of shower.

Where herein the term "forwardly" is used it shall mean the general direction in which the tobacco is fed by the tobacco feeding apparatus 25 to the cigarette making or tobacco packaging machine.

According to one form of the present invention there is provided in the feeding of tobacco to a cigarette making or tobacco packaging machine, a method of forming a tobacco carpet by feeding tobacco forwardly to a position at which its velocity is reduced whilst simultaneously confining said tobacco within a passage or a chamber which embraces the region of reduction of 30 velocity in such a manner that compacting of tobacco is brought about by compression produced by said reduction of velocity in said passage or chamber.

According to another form of the invention 40 there is provided in the feeding of tobacco, forming a carpet of tobacco on the surface of a conveyor, moving the carpet forwardly to a position at which its velocity is reduced and confining it within predetermined limits of thickness at or in the region of that position.

According to a further form of the present invention there is provided in a cigarette making or tobacco packaging machine, a method of feeding tobacco comprising the steps of forming tobacco into a carpet on the surface of a conveyor, moving the carpet forwardly to a position at which its velocity is reduced whilst simultaneously confining the carpet transversely of its direction of movement within a passage or a chamber which embraces the region of reduction of 45

velocity in such manner that compacting of the carpet is brought about by compression produced by said reduction of velocity in said passage or chamber, and transferring tobacco from the compacted carpet to the cigarette making or tobacco packaging machine (e. g., by picking and showering it into the trough of the machine). 5

In a still further form of the present invention there is provided in a cigarette making or tobacco packaging machine, a method of feeding tobacco to the machine, said method consisting in forming a tobacco carpet by building it up endwise, taking tobacco away from the opposite end of the carpet to that at which it is built up and delivering the tobacco so removed 10 to the machine. 15

Again, according to the present invention there is provided in the feeding of tobacco to a cigarette making or tobacco packaging machine, a method of forming a tobacco carpet by feeding shreds or 20 particles of tobacco forwardly to a position at which their velocity is reduced, whilst simultaneously confining the shreds or particles transversely of their direction of movement within a chamber or a passage which embraces the region 25 of reduction of velocity in such manner that the carpet is built up endwise within the chamber or passage.

In another form according to the present invention there is provided in the feeding of tobacco to a cigarette making or tobacco packaging machine a method of forming a tobacco carpet by feeding shreds or particles of tobacco forwardly into a chamber or a passage, impeding the exit of the tobacco from the chamber or passage, and removing the tobacco from the chamber or passage with a velocity which is less than that at which it enters, whereby a tobacco carpet is built up in the chamber or passage from the shreds or particles of tobacco. 30 35 40

Still further according to the present invention there is provided in or for tobacco feeding apparatus, conveyor means to feed a carpet of tobacco forwardly, a device disposed in the path of the carpet to impede its forward movement, 45 said device being movable to feed the carpet forwardly with a slower velocity than that at which it is moved by the conveyor and control means operative upon and arranged transversely of the carpet considered in the direction of movement thereof, said control means being disposed at and in the region of the point at which the velocity of tobacco carpet is changed to confine the tobacco within predetermined cross-sectional limits. 50

Further, according to the present invention 55

there is provided in or for tobacco feeding apparatus, means to feed separated shreds or particles of tobacco into a chamber or passage provided with an inlet and an outlet at opposite ends thereof, means to move the tobacco in the chamber or passage towards the outlet thereof and a device disposed at the outlet of the chamber or passage to impede the exit of the tobacco therefrom, said device being operative to remove tobacco from the chamber or passage at a slower rate than that at which it is fed thereto.

Again there is provided in or for tobacco feeding apparatus, mechanism operative to form a tobacco carpet by building up the same endwise, said mechanism comprising a chamber or a passage into which shreds or particles of tobacco are moved (e. g., by showering), the chamber or passage having at least two oppositely disposed movable surfaces each of which is movable in the same general direction to move the carpet forwardly as it is built up and a device disposed at the outlet of the chamber or passage to impede the exit of the carpet, said device being operative to remove the carpet from the chamber or passage at a slower rate than that at which tobacco is moved thereto to form the carpet. The conveyor may comprise a smooth movable surface, e. g., a rotatable drum, or an endless band and the control means may comprise a member or members disposed above the conveyor to engage with the upper surface of the carpet, the surface or surfaces of said member or members which engage with the carpet being either stationary or movable in the direction in which the carpet is being moved, but at a slower speed.

In a still further form according to the present invention there is provided in the feeding of tobacco, a method comprising feeding tobacco through confining walls of a chamber or passage and receiving it as it issues on a carded surface which is moving at a slower speed than that of the tobacco entering the chamber, whereby compacting of the tobacco results in the chamber or passage due to the reduction of velocity of the tobacco in said chamber or passage.

Again, there is provided in or for tobacco feeding apparatus, a passage, means to feed tobacco through the passage and a carded surface arranged to receive tobacco as it issues from the passage and arranged to remove said tobacco at a slower velocity than that at which the tobacco entered the passage.

The invention will now be more particularly described by way of example with reference to the accompanying drawings, in which:—

Figure 1 is a sectional view of one form of tobacco feeding apparatus constructed in accordance with the invention.

Figure 2 is a sectional view showing a portion of Figure 1 drawn to an enlarged scale.

Figure 3 is a sectional view of a portion of Figure 1 drawn to an enlarged scale and showing a modified form of the invention.

Figure 4 is a front elevation, with parts broken away, of the apparatus as viewed from the left of Figure 2.

Figure 5 is a sectional view of a further modified form of the invention.

Figure 6 is a side view, drawn to an enlarged scale, of the form of the tobacco-feeding mechanism shown in section in Figure 1.

Figure 7 is a view, with some parts omitted, taken on the side of the mechanism opposite to that of Figure 6.

Figure 8 is a view, with parts broken away,

of the apparatus as viewed in the direction of the arrow 8 of Figure 2.

Like references refer to like parts throughout the specification and drawings.

Referring to Figures 1 and 2, tobacco is contained in a hopper 1, and is supported in the hopper by a roller 2 which feeds the mass of tobacco towards a combing roller 3. The combing roller takes a quantity of tobacco from the mass contained in the hopper 1 and carries it upwardly as shown by the arrow. The tobacco is arranged over the surface of the combing roller 3 in the form of a carpet, and an oscillating raking device 4 is arranged to sweep over the surface of the carpet carried by the roller 3 in order to regulate the quantity of tobacco carried upwardly thereby. A brushing roller 5 rotating in the direction shown in Figure 1 is arranged to brush over the surface of the tobacco carpet carried by the combing roller and to brush back any surplus tobacco which may be carried thereby.

The brushing roller 5 is driven by means of a ratchet wheel 158 (Fig. 6) and pawl 151, which latter is carried by an arm 152 pivoted on the shaft of the roller 5. The arm 152 is oscillated by means of a rod 153 which connects the arm 152 with an eccentric strap 154 mounted on an eccentric 156 fixed to the shaft 108 referred to later. A pawl 155 prevents the ratchet wheel 158 from running in the reverse direction and an adjustable brake band 157, Figure 7, prevents the roller 5, which is of considerable weight, from overrunning.

A rotary cleaning device 158 is provided for cleaning the surface of the brushing roller 5 and is driven by a pulley 159 on the spindle of the picker roller 8 referred to below, the pulley 159 being connected to another pulley 160 on the spindle of the rotary cleaner 158 by a belt 161. In the junction formed between the rollers 3 and 5 a roll of tobacco may be formed and maintained from which tobacco is taken by the combing roller 3. The raking device 4 is arranged to rake and to trim the roll of tobacco in a known manner, whilst a presser device 6 is arranged periodically to press the tobacco roll against the carding of the combing roller 3. The mechanism for operating the raking and pressing devices is described later with reference to Figures 6 and 7. The raking device 4 and pressing device 6 do not form any part of the present invention, but are described as constituting elements which assist in the feeding of tobacco from the hopper 1.

After the tobacco carried by the combing roller 3 has passed beneath the brushing roller 5 it is carried to a point at which spring comb elements 7 press the tobacco against the combing roller whilst a picker roller 8 is arranged to pick the tobacco from the combing roller 3 and to shower it on to the surface of a smooth roller 9.

The roller 8 is rotated with a velocity such that the shreds or particles of tobacco showered on to the surface of the roller by the picker roller 8 do not become superimposed one upon the other to form a carpet, but are maintained as far as possible in a substantially separated condition. (This is the meaning to be given herein to the word "separated" when referring to tobacco shreds or particles.) The shreds or particles of tobacco on the surface of the roller 8 are moved beneath a roller 16 rotating in the direction shown in Figures 1 and 2, and are thereafter moved beneath a shroud 11. It will

be seen from Figures 1 and 2 that the surface of the roller 9, together with the roller 10 and shroud 11 and side walls 40 (see Figure 4) form a chamber or passage into which the shreds or particles of tobacco are passed, the entrance to the chamber being open whilst at the outlet end of the chamber there is provided a rotatable carded roller 12, whose direction of rotation is opposite to that of the smooth roller 9, and which rotates at a peripheral speed less than that of the smooth roller 9 and thus impedes the forward movement of the tobacco.

The shroud 11 is bent upwardly at the inlet end of the chamber to form a bell mouth, and at the opposite end is brought as close as possible to the surface of the carded roller 12, whilst allowing for any movement to be imparted to the shroud. The side walls 40 consist of flat plates fixed to the frames of the machine so that they embrace the end faces of the roller 9 and the shroud 11. They are not shown in Figures 6 and 7, to avoid obscuring other parts of the mechanism, but their shape is clear from Figure 2.

The inner face or surface of the shroud 11 is substantially parallel to the surface of the roller 9, but it is found that a very slight convergence of the surfaces 9 and 11 from the inlet end to the outlet can be used, provided that the convergence is not so great as to cause choking or jamming in the chamber.

The shreds or particles of tobacco are carried by the roller 9 into the chamber and their exit therefrom is impeded by the roller 12 which has a slower peripheral speed than has the roller 9 so that a carpet of tobacco is built up endwise within the chamber, and the tobacco is at the same time confined within predetermined cross-sectional limits by the confining walls of the chamber or passage. The roller 12 removes tobacco from the carpet built up within the chamber at a slower rate than that at which the tobacco is fed into the chamber.

Beneath the carded roller 12 is a concave shroud 13 which is just clear of the carding of the roller 12, and which acts as a scraper on the surface of the smooth roller 9, so that the tobacco carpet is removed from the faster moving roller 9 and is carried away positively by the teeth of the carded roller 12 at the opposite end to that at which the carpet is built up. The tobacco which is taken by the roller 12 and carried over the surface of the concave shroud 13 is picked therefrom by a picker roller 14, and is showered into a trough 15 of the machine to which the tobacco is being fed. The trough 15 shown in the drawings represents a well known form of trough used on continuous rod cigarette making machines, or the trough may be used on a tobacco packaging machine in which, for example, a continuous tobacco rod filler is formed.

The carpet which is built up in the chamber is continuously moved towards the roller 12 and in the constructions shown in Figures 1, 2 and 4, in order to assist the forward movement of the tobacco towards the roller 12, the shroud 11 is carried by links 16 and 17 which are mounted on eccentric spindles 18 and 19 rotatably supported in brackets 139 fixed to the machine frame as shown in Figures 6, 7 and 8. In Figure 6 the bracket is broken to expose the shroud 11. The spindles are rotated as described below by means driven from the main drive of the machine. The effect of the rotation of the spindles 18 and 19

is to cause the shroud 11 to move through a curvilinear path, so that the shroud approaches and recedes from the surface of the smooth roller 9, and when it is in the position at which it is nearest to the surface of the roller 9, the under surface of the shroud 11 is moving in the same general direction as that in which the surface of the roller 9 is moving. The speed of the shroud is slower than the peripheral speed of the roller 9, but greater than the peripheral speed of the 10 roller 12.

It will be appreciated that instead of the shroud 11 being movable as above described, it may be secured in a fixed position, and in such cases the tobacco carpet formed in the chamber is moved forwardly towards the roller 12 entirely by the action of the roller 9. It is found, however, that the moving shroud 11 is better in practice than a stationary shroud.

Referring to Figure 6, the picker roller 14, spindles 18 and 19, and the roller 10, all receive motion from a belt 123 which is secured to a pulley on a shaft not shown, which is driven by a motor or other suitable means. Belt 123, as will be seen from Figure 6 after passing round a guide pulley 136, drives a pulley 124 secured to the spindle 125 of the picker roller 14, and also rotates a pulley 137 fixed to a spindle 126 to which is secured a gear wheel 127 (see Figure 8) the gear wheel 127 meshing with gears 128 and 129 secured to the spindles 18 and 19 respectively. The belt 123 also drives a pulley 130 secured to a shaft 131 which also carries the picker roller 8 on which shaft is secured a further pulley 132 which is connected by a belt 133 with a pulley 134 on the shaft 135 of the roller 10. To permit belt 123 to clear the spindle 135 it passes over a jockey pulley 138 loosely mounted on said spindle, see Figures 6 and 8.

Referring to Figures 7 and 8, the whole of the tobacco feeding apparatus is driven by a belt 100 which receives motion from a pulley, not shown, secured to a shaft which is driven by an electric motor or other suitable means. Another pulley on said shaft drives the belt 123 referred to above. The belt 100 drives a pulley 101 secured to a shaft 102. To the shaft 102 there is secured a gear wheel 103, with which meshes a gear wheel 104 secured to a spindle 105. To the spindle 105 there is also secured a gear wheel 106 which meshes with a gear wheel 107 secured to a spindle 108, and to the spindle 108 there is secured a gear wheel 109 which meshes with a gear wheel 110 secured to a shaft 111. To the shaft 111 there is secured a further gear wheel 112 which meshes with a gear wheel 113 secured to the shaft 114 of the carded combing roller 3. Four of the gears just referred to lie in one plane and four in another plane behind the first four. The four gears at the rear are indicated by vertical shading. To the shaft 111 there is also secured a sprocket 115 and a chain 116 connects the sprocket 115 with a sprocket 117 secured to a shaft 118 on which is secured a gear wheel 119 meshing with a gear wheel 120, the gear wheel 120 meshing with a further gear wheel 121 secured to the shaft 122 of the carded roller 12.

Referring more particularly to Figure 6, the shaft 114 of the combing roller carries a sprocket 165 which is connected by a chain 166 to another sprocket 167 fixed on the shaft of the feeding roller 2 and said roller is thereby rotated at the proper speed.

On the shaft 108 behind the eccentric 156 is 75

mounted a further sprocket 168 connected by a chain 169 to another sprocket 170 on the shaft of the smooth roller 9 which thus rotates at the correct speed relatively to rollers 2 and 3.

5 A further sprocket 171 on shaft 168 and in front of the eccentric 166 is connected by a chain 172 to a sprocket 173 at the upper part of the figure. This sprocket is fixed on a stub shaft 174 mounted in a bearing 188 and on the other end 10 of the stub shaft is a crank 189 carrying a crank pin 175 to which is attached a connecting rod 176. The upper end of the connecting rod is pivoted to a lever 177 on a shaft 178 mounted in bearings 179 at the top of the hopper so that as 15 the crank disc rotates the shaft 178 is oscillated. Two short levers 180 are fixed to the shaft 178 and at their free ends carry projections, not shown, which rest against two levers 181, loosely mounted on the shaft 178. Therefore, as the 20 shaft oscillates in one direction these levers are raised. In Figure 1 the parts 176, 177, 178, 179, 181 and 188 are also indicated and from that figure it will be seen that each lever 181 just referred to constitutes the upper lever of a parallel 25 link system completed by a lever 182 pivoted to the foot of the bearing, and a link 183 attached to the free ends of levers 181 and 182. An extension of link 183 carries the presser 6 which is thus periodically lifted and then permitted to fall to 30 a position determined by the quantity of tobacco present, i. e., the roll in the junction between rollers 3 and 5.

Another link 184 attached to the connecting rod at point 185 is attached at its other end to a short crank or lever 186. The latter is fixed at its other end to the spindle 187 which supports the raking device 4 which is therefore oscillated at regular intervals to rake and trim the roll of tobacco.

40 In all the chain gearing above described with reference to Figures 6 and 7, small sprockets are shown which serve as chain tighteners and/or guides to keep the chains in the proper paths to avoid fouling other portions of the machinery. 45 These sprockets have not been referred to in detail, as it is not considered necessary.

In a modified form of the invention, as illustrated in Figure 3, the shroud 11 is replaced by a plurality of juxtaposed rollers 20, the axes 50 of rotation of the rollers being disposed on a line substantially parallel with the periphery of the roller 9 with or without the slight convergence towards the exit mentioned in connection with the shroud 11. The longitudinal axes of the 55 rollers are parallel with the surface of the roller 9. The rollers 20 are rotated in the direction indicated in Figure 3, but the surface speed of the rollers 20 is less than the surface speed of the roller 9 and greater than that of the roller 12. 60 Side walls 40' are provided and operate in the manner previously described with reference to Figure 2. A plate 30 is provided between the rollers 20 and 12 respectively if it is found that the gap between the rollers is so large as to 65 versely affect the packing of the tobacco within the restricted space inside the chamber.

In this modified form of the invention the carpet is built up endwise within the chamber or passage in the manner previously described, and 70 the carpet is fed forwardly towards the roller 12 by the action of the rollers 9 and 20, and tobacco is taken away by the roller 12 from the leading end of the carpet as in the previous example.

In a further modified form of the invention 75 as shown in Figure 5, the shroud is constituted

by an endless band 21 or by a plurality of endless bands and the surface speed of the band or bands is less than the peripheral speed of the smooth band 90 but greater than that of the roller 12. In this example, the tobacco, as will be seen from 5 the drawings, is showered onto an endless band 90 having a non-carded surface and reinforcing plates 91 and 92 are provided. As in the construction shown in Figure 3, a plate 30 is provided, if necessary, between the roller 12 and 10 roller or rollers 31 around which the band 21 passes.

It will be appreciated that instead of the endless moving band 21, a plate could be provided having its under surface substantially parallel 15 to the surface of the band 90. This plate may be either moved as in Figure 2, or stationary and may converge slightly as stated with regard to the construction shown in Figure 2. Alternatively, a series of juxtaposed rollers could be arranged to form the top wall of the control 20 chamber.

In all the examples given, the height of the moving surface of the shroud above the smooth roller or the endless band is equal to the thickness 25 of carpet desired, but in the construction shown in Figures 1 and 2 where the height of the shroud 11 continuously varies, the thickness of the carpet will be equal to the distance of the shroud from the roller 9 when those two are near- 30 est to one another.

It will be understood that the opposed walls of the chambers may, if desired, diverge slightly from the inlet end towards the outlet instead of being exactly parallel or slightly convergent. The 35 side walls 40, however, may be given, if desired, a greater degree of divergence or convergence since they are a considerable distance apart and only act on the tobacco at the extreme edges of the carpet, which, as is well known, may be of 40 considerable width.

It will be seen that the main body of the tobacco forming the carpet which is greater in width than in thickness is confined solely between the surfaces which engage the top and bottom 45 respectively of the carpet, and the side guides 40 have little or no effect on the carpet except to keep the edges under proper control.

If necessary, the height of the shroud above the smooth roller or conveyor may be adjustable 50 either manually or automatically to prevent the length of the endwise built carpet becoming either too small or too big. If the length (considered in the direction of movement) of the endwise built carpet becomes too small there is a danger of 55 it being taken away wholly by the carded roller 12. On the other hand, if the length of the carpet becomes too great, there will be a danger of a large accumulation of tobacco at the entrance of the shroud, whereby the feed will become 60 choked. In addition to or instead of altering the height of the shroud the speed of the moving surfaces may be altered to take more or less tobacco to the carded roller 12, or again, the quantity of tobacco fed to the smooth roller 9 or 65 smooth belt 90, may be varied in any suitable way. Any two or more of these adjustments may be made simultaneously either manually or automatically.

In another modified form of the invention, 70 instead of rotating the roller 9 or the belt 90 at a speed such that the shreds or particles of tobacco received from the picker roller 8 are arranged in a separated condition on the surface of the roller 9 or belt 90 (as described in the pre- 75

vious examples), the roller or belt as the case may be, in any of the alternative constructions, may be given a surface speed such that the tobacco showered from the picker 8 is formed into a carpet on the surface of the roller 9 or belt 90 in the usual manner, that is, the manner customary when the tobacco is showered on to a carded surface. The tobacco carpet so formed is passed beneath the compression roller 10 and into the 10 chamber or passage previously described, and its forward movement is impeded by the roller 12 as above described. In this form of the invention, the roller 12 has a slower peripheral speed than that of the smooth roller 9 or belt 90, and the 15 carpet is therefore fed into the chamber or passage with a greater velocity than that at which it is removed from the chamber or passage by the roller 12. The carpet is in this way packed or gathered in its direction of movement, and has 20 when it is removed from the chamber by the slower moving carded roller 12, a more uniform density than have tobacco carpets formed in the usual well known manner. The roller 12 constitutes a resistance or impediment to the forward movement of the carpet at its original velocity, so that the tobacco is gathered lengthwise of the carpet, and the density of the sparsely filled portions of the carpet is raised.

It will be understood that in cases where the 30 shroud comprises a stationary surface and/or where the tobacco is already in the form of a carpet before entering the chamber, the surface of the roller 9 or the belt 90 will have to be sufficiently rough so that at the speed of movement 35 of the surface there will be a sufficient impelling force exerted on the tobacco to carry it forward, but at the same time it should be appreciated that the surface should be sufficiently smooth to allow it to slip when the tobacco has been packed 40 to a sufficient density between the shroud and the moving surface.

Where the tobacco is formed as a carpet on the roller 9 before being gathered in the chamber, it will be appreciated that the resulting 45 carpet will not be as good as in the case where the carpet is built up by endwise impact of the tobacco shreds in the chamber, but by gathering the carpet an improved result is obtained, since the gathering of the tobacco will help to reduce 50 the inequalities in the carpet.

What I claim as my invention and desire to 55 secure by Letters Patent is:—

1. A method of forming a tobacco carpet which comprises the steps of showering tobacco particles downwardly, intercepting the showered particles and conveying the same laterally at a rate sufficient to form a stream having a depth much less than that desired in the completely formed carpet, and retarding the movement of 60 the stream to cause the trailing particles to impact on the leading particles while confining the stream against appreciable lateral expansion, the extent of retardation of the stream being sufficient to build up a tobacco carpet of the desired depth.

2. A method of forming a tobacco carpet which 65 comprises the steps of showering tobacco particles downwardly, intercepting the showered particles and conveying the same laterally at a rate sufficient to form a stream having substantially no built-up depth resulting from superpositioning of particles, and retarding the movement of the stream to cause the trailing particles to impact on the leading particles while confining the stream against appreciable lateral ex-

pansion, the extent of retardation of the stream being sufficient to build up a tobacco carpet of the desired depth.

3. In apparatus for forming a tobacco carpet, the combination with means for showering tobacco particles downwardly, of a conveyor receiving the showered particles and feeding the same transversely of the shower in a stream, the rate of movement of said conveyor being so controlled with respect to the density of the shower as to form a stream of substantially less depth than that desired in the completed carpet, means retarding the movement of the conveyed stream, and means adjacent the point of retardation of the stream to confine the same laterally, whereby the impact of the more rapidly moving particles on the retarded particles will effect compacting thereof to build up the depth of the stream to that required for the completed carpet.

4. In apparatus for forming a tobacco carpet, the combination with means for showering tobacco particles downwardly, of a conveyor receiving the showered particles and feeding the same transversely of the shower in a stream, the rate 25 of movement of said conveyor being so controlled with respect to the density of the shower as to form a stream lacking in pronounced superimpositioning of particles and accordingly of substantially less depth than that desired in the 30 completed carpet, means retarding the movement of the conveyed stream, and means adjacent the point of retardation of the stream to confine the same laterally, whereby the impact 35 of the more rapidly moving particles on the retarded particles will effect compacting thereof to build up the depth of the stream to that required for the completed carpet.

5. In apparatus for forming a tobacco carpet, the combination with means for showering tobacco particles downwardly, of a conveyor receiving the showered particles and feeding the same transversely of the shower in a stream, the rate of movement of said conveyor being so controlled with respect to the density of the shower as to 40 form a stream of substantially less depth than that desired in the completed carpet, means retarding the movement of the conveyed stream, means adjacent the point of retardation of the stream to confine the same laterally, and means 45 disposed above said stream and supported for movement toward or away from the same during operation of the apparatus for determining and regulating the depth of the carpet, whereby the impact of the more rapidly moving particles on the retarded particles will effect compacting thereof to build up the depth of the stream to 50 that required for the completed carpet.

6. In apparatus for forming a tobacco carpet, the combination with means for showering tobacco particles downwardly, of a conveyor receiving the showered particles and feeding the same transversely of the shower in a stream, said conveyor comprising a rotatable drum having a tobacco receiving peripheral surface, the rate of movement of said conveyor being so controlled with respect to the density of the shower as to 60 form a stream of substantially less depth than that desired in the completed carpet, means retarding the movement of the conveyed stream, and means adjacent the point of retardation of the stream to confine the same laterally, whereby the impact of the more rapidly moving particles on the retarded particles will effect compacting 65

thereof to build up the depth of the stream to that required for the completed carpet.

7. In apparatus for forming a tobacco carpet, the combination with means for showering tobacco particles downwardly, of a conveyor receiving the showered particles and feeding the same transversely of the shower in a stream, the rate of movement of said conveyor being so controlled with respect to the density of the shower as to form a stream of substantially less depth than that desired in the completed carpet, means retarding the movement of the conveyed stream, means adjacent the point of retardation of the stream to confine the same laterally, whereby the impact of the more rapidly moving particles on the retarded particles will effect compacting thereof to build up the depth of the stream to that required for the completed carpet, and means disposed above said stream adjacent the point of formation of the carpet for limiting the depth of the carpet, said last named means including a plurality of rollers having the axes thereof directed transversely of said stream.

8. In apparatus for forming a tobacco carpet, the combination with means for showering tobacco particles, of a conveyor receiving the showered particles and feeding the same in a stream, the rate of movement of said conveyor being so controlled with respect to the density of the shower as to form a stream of substantially less depth than that desired in the completed carpet, means retarding the movement of the conveyed stream, and means adjacent the point of retardation of the stream to confine the same laterally, whereby the impact of the more rapidly moving particles on the retarded particles will effect compacting thereof to build up the depth of the stream to that required for the completed carpet.

9. In apparatus for forming a tobacco carpet, the combination with means for showering tobacco particles, of a conveyor receiving the showered particles and feeding the same in a stream, the rate of movement of said conveyor being so controlled with respect to the density of the shower as to form a stream lacking in pronounced superimposition of particles and accordingly of substantially less depth than that desired in the completed carpet, means retarding the movement of the conveyed stream, and means adjacent the point of retardation of the stream to confine the same laterally, whereby the impact of the more rapidly moving particles on the retarded particles will effect compacting thereof to build up the depth of the stream to that required for the completed carpet.

10. In apparatus for forming a tobacco carpet, the combination with means to feed tobacco particles, of a conveyor having a surface to receive said particles and feed them forwardly as a stream, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will compact the stream and increase the mass thereof, said conveyor having movement relative to said surface opposed to the surface of the conveyor.

11. In apparatus for forming a tobacco carpet, the combination with means to feed tobacco particles, of a conveyor to receive said particles and feed them forwardly as a stream, said conveyor

comprising a rotatable drum having a tobacco receiving peripheral surface, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will compact the stream and increase the mass thereof, said conveyor having movement relative to said surface opposed to the surface of the conveyor.

12. In apparatus for forming a tobacco carpet, the combination with means to feed tobacco particles, of a conveyor having a surface to receive said particles and feed them forwardly as a stream, the rate of movement of said conveyor being so controlled with respect to the density of the tobacco fed thereto as to form a stream of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required in the completed carpet, said conveyor having movement relative to said surface opposed to the surface of the conveyor.

13. In apparatus for forming a tobacco carpet, the combination with means to feed tobacco particles, of a conveyor to receive said particles and feed them forwardly as a stream, said conveyor comprising a rotatable drum having a tobacco receiving peripheral surface, the rate of movement of said conveyor being so controlled with respect to the density of the tobacco fed thereto as to form a stream of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required for the completed carpet, said conveyor having movement relative to said surface opposed to the surface of the conveyor.

14. In apparatus for forming a tobacco carpet, the combination with means to feed tobacco particles, of a conveyor having a surface to receive said particles and feed them forwardly as a stream, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will compact the stream and increase the mass thereof, said means and the surface of said conveyor forming a passage through which the stream is fed, said passage being of sufficient length to extend on either side of the point of compacting of the stream as measured in the direction of movement thereof, said conveyor having movement relative to the opposed surface of the passage.

15. In apparatus for forming a tobacco carpet, the combination with means to feed tobacco particles, of a conveyor to receive said particles and feed them forwardly as a stream, said conveyor comprising a rotatable drum having a tobacco receiving peripheral surface, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will compact the stream and increase the mass thereof to the desired mass, said means and the conveyor surface forming a passage through which the stream is fed, said passage being of sufficient length to extend on either side of the point of compacting of the stream as measured in the direction of movement thereof, said conveyor surface having movement relative to said opposed surface of the passage.
16. In apparatus for forming a tobacco carpet, the combination with means to feed tobacco particles, of a conveyor having a surface to receive said particles and feed them forwardly as a stream, the rate of movement of said conveyor being so controlled with respect to the density of the tobacco fed thereto as to form a stream of substantially less depth than that desired in the completed carpet, means retarding the movement of the conveyed stream, and means adjacent the points of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required in the completed carpet, said means and the conveyor surface forming a passage through which the stream is fed, said passage being of sufficient length to extend on either side of the point of compacting of the stream as measured in the direction of movement thereof, said conveyor having movement relative to the opposed surface of the passage.
17. In apparatus for forming a tobacco carpet, the combination with means to feed tobacco particles, of a conveyor to receive said particles and feed them forwardly as a stream, said conveyor comprising a rotatable drum having a tobacco receiving peripheral surface, the rate of movement of said conveyor being so controlled with respect to the density of the tobacco fed thereto as to form a stream of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required for the completed carpet, said means and said conveyor surface forming a passage through which the stream is fed, said passage being of sufficient length to extend on either side of the point of compacting of the stream as measured in the direction of movement thereof, said conveyor having movement relative to the opposed surface of the passage.
18. In apparatus for forming a tobacco carpet, the combination with means for showering tobacco particles, of a conveyor having a surface for receiving the showered particles and for feeding the same in a stream, the rate of movement of said conveyor surface being so controlled with respect to the density of the shower as to form a stream of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required for the completed carpet, said conveyor having movement relative to said surface opposed to the surface of the conveyor.
19. In apparatus for forming a tobacco carpet, the combination with means for showering tobacco particles, of a conveyor having a surface for receiving the showered particles and for feeding the same in a stream, the rate of movement of said conveyor surface being so controlled with respect to the density of the shower as to form a stream lacking in pronounced superimpositioning of particles and accordingly of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required for the completed carpet, said conveyor having movement relative to said surface opposed to the surface of the conveyor.
20. In apparatus for forming a tobacco carpet, the combination with means for showering tobacco particles downwardly, of a conveyor having a surface for receiving the showered particles and for feeding the same transversely of the shower in a stream, the rate of movement of said conveyor surface being so controlled with respect to the density of the shower as to form a stream of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required for the completed carpet, said conveyor having movement relative to said surface opposed to the surface of the conveyor.
21. In apparatus for forming a tobacco carpet, the combination with means for showering tobacco particles downwardly, of a conveyor having a surface for receiving the showered particles and for feeding the same transversely of the shower in a stream, the rate of movement of said conveyor surface being so controlled with respect to the density of the shower as to form a stream lacking in pronounced superimpositioning of particles and accordingly of substantially less depth than that desired in the completed carpet, means

retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required for the completed carpet, said conveyor surface having movement relative to said surface opposed to the surface of the conveyor.

22. In apparatus for forming a tobacco carpet, the combination with means for showering tobacco particles downwardly, of a conveyor having a surface for receiving the showered particles and for feeding the same transversely of the shower in a stream, the rate of movement of said conveyor surface being so controlled with respect to the density of the shower as to form a stream of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, said means being supported for movement toward or away from the stream during operation of the apparatus for determining and regulating the depth of the carpet, whereby the impact of the more rapidly moving particles on the retarded particles will effect compacting thereof to build up the depth of the stream to that required for the completed carpet, said conveyor surface having movement relative to said surface opposed to the surface of the conveyor.

23. In apparatus for forming a tobacco carpet, the combination with means for showering tobacco particles downwardly, of a conveyor having a surface for receiving the showered particles and for feeding the same transversely of the shower in a stream, said conveyor comprising a rotatable drum having a tobacco receiving peripheral surface, the rate of movement of said conveyor surface being so controlled with respect to the density of the shower as to form a stream of substantially less depth than that desired in the completed carpet, means retarding the movement of the conveyed stream, and means adjacent the point of retardation of the stream to confine the tobacco laterally, a part at least of said means presenting a surface opposed to that of the conveyor to control the thickness of the carpet, whereby the impact of the more rapidly moving particles on the retarded particles will effect compacting thereof to build up the depth of the stream to that required for the completed carpet, said conveyor surface having movement relative to said surface opposed to the surface of the conveyor.

24. In apparatus for forming a tobacco carpet, the combination of opposed elements arranged to engage opposite sides of a tobacco stream, one of said elements comprising a conveyor to feed the tobacco forwardly, and one at least of said elements being movable towards and away from the opposed element during operation of the apparatus, and means to retard the movement of the tobacco when passing between the opposed elements whereby the stream is subjected to endwise compacting to form a tobacco carpet.

WALTER EVERETT MOLINS.
